BY
LAWRENCE A. JOHNSON
ATTORNEY

UNITED STATES PATENT OFFICE

HERMAN C. HOGREFE, OF SAN FRANCISCO, CALIFORNIA

DOOR HOLDER

Application filed June 18, 1928, Serial No. 286,146.

This invention relates to improvements in door holders and resides in the provision of a simple and inexpensive device of this nature which may be quickly and easily installed and will operate automatically incident to the opening of the door into a predetermined position to engage and hold the door against unintentional closing, said device being moved to release the door when the door is intentionally moved as when closing the same.

An object of the invention is to provide a door holder of the character described which has a moment of inertia sufficient to hold itself in any position into which it is moved on the surface on which the door holder is arranged, whereby when the door is engaged with the holder, said device will hold the door against unintentional closing.

A further object of the invention is to provide a door holder of the character described which is provided with a simple but effective means for locking the holder against movement, whereby the door may be locked against closing except when forcefully moved to close the same, the employment of said means being desirable in some instances where the doors are subjected to heavy wind pressures or drafts which might be sufficient to overcome the inertia moment of the holder.

A further object of the invention is to provide a holder of the character described which may be quickly and easily installed without necessitating any change in the construction of the floor or in the door.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to without departing from the spirit or sacrificing any of the advantages of the invention.

Referring to the drawings:

Fig. 1 represents a top plan view of a door holder of my invention.

Fig. 2 represents a sectional view taken on the plane of line 2—2 of Fig. 1.

Fig. 3 represents a plan view of a door showing the door frame in section, also showing the holder of my invention as it would appear when in use to hold the door open.

Fig. 4 is a view similar to Fig. 3 but showing the same in position to release the door.

Fig. 5 is a rear elevation of the holder.

One embodiment of my invention as shown in detail in the accompanying drawings comprises a substantially V-shaped body member 1, made of iron or some other suitable heavy material, whereby the body member may be made comparatively small and compact and yet have a moment of inertia such that it will remain in any position into which it is moved and serve as a means for holding a door against unintentional closing.

The body member is pivotally mounted in place on a floor A, in position such that when the door B is opened, it will engage in the slot C and move the body from position shown in Fig. 4 to position shown in Fig. 3. Due to the inertia moment of the body member, it will remain in the last named position and hold the door against being unintentionally closed. On intentionally closing the door, the body member will be moved into position shown in Fig. 3 and remain there, whereby on again opening the door it will be ready to again automatically hold the door.

The body member 1, is provided with a substantially central opening 2 through which a vertical shaft 3 extends. The lower end of the shaft is threaded and screwed into a countersunk socket 4 in the floor A. The shaft has a head 5 normally spaced above the top of the body, which head is of greater diameter than the opening 2. It will thus be seen that the device may be easily and quickly installed without necessitating any material changing of the construction of the floor. The shaft may be anchored in the floor in any suitable manner other than shown. However, the present method is suitable for concrete and

cement floors such as found in basements and garages.

The holder of this invention although especially designed for garage doors may be used with other doors with equal facility.

5 I may use a locking means such as shown in the drawings for the purpose of holding doors which are subjected to strong wind pressures, which pressures would overcome the weight of the body member and tend to 10 close the door. This means comprises interfitting parts carried on the shaft and member 1 respectively, which parts will interfit when the holder is moved into holding and non-holding positions, but will release 15 when the door is intentionally moved. One of the parts is in the form of a cylindrical pin 6 inserted transversely through the shaft 3 and lying close to the floor. The other part is in the form of grooves 7, 8 and 20 9 formed in the bottom of the body member. The groove 7 receives the pin when the holder is in holding position. With a door hung and operating as shown in Fig. 4, the groove 8 receives the pin when the 25 door is moved from open to closed position. In this way the holder is held by the interfitting parts (the pin 6 and grooves 7 and 8) when in both operative and inoperative 30 positions. By this locking of the holder in operative position, the door will be held open against strong wind pressure and by locking the holder in inoperative position, the automatic holding operation is sure to take place on the swinging of the door into 35 open position.

The sides of the slots 7, 8 and 9 are beveled or rounded so that the holder will readily disengage from the pin 6 when moved 40 with the door in contact therewith as in closing or opening the door. The holder lifts clear of the pins by this cam action, the head 5, limiting this upward movement. The extra slot 9 comes into use when the 45 door is hung to swing both ways. By having the two slots 8 and 9, the holder may be used with right or left hung doors.

Having thus described this invention, what I claim and desire to secure by Letters 50 Patent is:

A door holder comprising a piece of material having a slot formed in a side thereof to receive the swinging edge of a door to move with and to hold said door in open position; a shaft fixed in the supporting surface for the holder, said piece of material being slidably and oscillatably mounted on the shaft in operative relation to the free edge of the door; the bottom face of said material having grooves therein; and a pin on the shaft adapted to engage said grooves upon movement of the material into predetermined positions, and to coact with said grooves for lifting the material on the shaft 65 so as to release the respective groove from

the pin upon intentional oscillation of the holder.

In testimony whereof, I have hereunto set my hand at San Francisco, California, this 23rd day of May, 1928.

HERMAN C. HOGREFE.
